UNITED STATES PATENT OFFICE.

EMIL KROUTL, OF BUDWEIS, CZECHOSLOVAKIA.

PENCIL HAVING A SLIDABLE LEAD.

Application filed September 14, 1922. Serial No. 588,110.

To all whom it may concern:

Be it known that I, EMIL KROUTL, a citizen of the Republic of Czechoslovakia, residing at Budweis, Czechoslovakia, have invented certain new and useful Improvements in and Relating to Pencils Having Slidable Lead, of which the following is a specification.

Pencils having a slidable lead are already known which comprise two cases adapted to slide within one another, a longitudinally adjustable rack for feeding forwardly the slidable lead, a locking catch adapted to engage and lock the rack against sliding backwardly, and a feed catch adapted to engage and feed forwardly the rack and thus also the lead. However these known pencils possess the drawback that in case it is desired to return the lead into the casing or if the rack has been fed forward its entire length the pencil has to be taken to pieces, e. g. the rack has to be removed through the forward end of the casing and has to be inserted again into the same by way of its rear end.

According to the present invention this drawback is removed in that a spring lever is attached to one of the cases and operated by pressure for raising the catches and interrupting the engagement between the two catches and the rack, so that the lead and rack or in case the lead is worn off entirely the rack alone can be returned into the pencil casing by placing the pencil in a vertical position or by exerting a pressure on the lead.

With the above object in view the invention consists of certain novel details of construction and combination of parts herein-after fully described and claimed, it being understood that various modifications may be made in the minor details of construction within the scope of the appended claims.

In the drawing a constructional example of the invention is shown.

Figs. 1, 2 and 3 are longitudinal sections through the pencil whereby its parts are illustrated in three different positions.

Fig. 4 illustrates a view of the pencil in a plane at right angles to Figs. 1, 2 and 3.

The pencil essentially comprises three parts.—An inner front case *e* to which a locking catch *g* and a spring lever *k* are fixed, a rear case *h* slidably arranged on the front case and provided with the feed-catch *ch*, and a toothed rack *a* sliding in the case *e* and whose teeth project into and are freely

accessible by means of a longitudinal slot *f* in the inner case *e*, and are guided by the slot, so that the rack cannot rotate in an axial direction. The free end of the locking catch *g* terminates in two arms *g*¹ and *g*², the end of the arm *g*¹ being bent inwardly and adapted to engage the rack *a*, while the end of the arm *g*² is bent downwardly and adapted to be engaged by the end *n*¹ of a semi-circular disengaging member *n*, which is fixed to the spring lever *k* and embraces the lower part of the case *e*. The feed-catch *ch* is formed in a manner similar to the locking catch *g*, the inwardly bent arm *ch*¹ of the feed-catch being adapted to engage the rack *a* and the downwardly bent arm *ch*² being adapted to be engaged by the end *n*² of the semi-circular disengaging member *n*. The arms of both catches are formed by longitudinally slotting the free ends of the said catches, whereby one arm of each catch (shown in full lines in Fig. 1) is bent downwardly at a right angle and forms the actual catch, whilst the other arm of each catch (the arm *ch*² being shown in dotted lines in Fig. 1) is so bent, that in its position of rest it will bear against the semi-circular member *n* of the spring lever *k*. Both catches may be lifted by exerting a pressure on the spring lever *k*.

A lead guide *m* is screwed or otherwise secured to the end of the case *e*. The two cases *h* and *e*, sliding on each other are connected by a wedge or bolt *l* in such a manner, that they can be moved towards or away from one another only for the length of one tooth of the rack. For this object the inner case is provided with a longitudinal slot or slit *p*, whose length corresponds to the width of the bolt and of one tooth, thus the bolt *l* riveted at both sides to the outer case *h* will have play in this slot to the extent of one tooth only. The lead rests against the end of a bar *b* which is secured to the rack *a*.

The pencil is actuated in the following manner.

The case *e* is grasped with one hand and the case *h* with the other hand, and both cases are pulled apart. Thereby the end of the feed-catch arm *ch*¹ will slide up the incline of the tooth and engage the next tooth of the rack *a*, as the latter is secured against sliding movement by the arm *g*¹ of the locking catch *g* (Fig. 1). However a further withdrawal of the case is prevented in that the bolt *l* secured to the case *h* has come to

rest against the end of the slot p in the case e and thus will limit the movement even on strongly pulling apart the two cases. In order to actually feed forward the lead, both cases have to be pressed into one another, whereby the feed-catch arm ch^1 will push the toothed rack in front of it, while the locking arm g^1 will slide up the inclined plane of the tooth and engage the next tooth (Fig. 2). However the forward feed is limited to one tooth only by means of the bolt l coming into contact with the left-hand-side edge of the slot p . This operation (repetition) may be repeated as many times as desired without injury to the lead until the lead will project out of the guide m for the desired length. If the uncovered part of the lead is worn out by writing the single repetition movement is again repeated, so that the lead will again project out of the guide m for the required length.

In order to return the lead, e. g. push the latter into the pencil-casing, the spring lever k arranged in the middle of the case e and provided with the semi-circular disengaging member n , is forced upwardly by means of depressing it with the aid of a push-button k^1 and thereby the ends n^1 and n^2 of the member n will engage the arms g^2 and ch^2 of the catches g and ch respectively and lift the two arms out of engagement with the rack, and the freed toothed rack will automatically slide rearwardly, e. g. inwardly, when placing the pencil in a vertical position, or the said rack may be pushed inwardly for any desired distance by exerting a pressure on the lead.

Both cases e and h are secured in a casing made of metal, wood, celluloid or the like, whereby the push-button k^1 for operating the lever k and which is secured to the disengaging member n passes through and out of the said casing (shown in dotted lines in Fig. 1). The forward feed of the lead is effected by moving the two cases against one another, while its return movement is accomplished by forcing inwardly the spring lever k by means of the push-button k^1 and simply pressing the pencil against the note-book.

The outside of the pencil may be of any desired shape.

Having thus described my invention, what I claim and desire to secure by Letters-Patent is:

1. A pencil having a slidable lead comprising in combination an inner case provided with a longitudinally extending slot, an outer case encasing the inner case, the two cases being adapted to slide within one another, a longitudinally adjustable toothed rack in the inner case for feeding forwardly the slidable lead, the teeth of the said rack projecting into and being freely accessible by means of the longitudinal slot in the inner case, a locking catch on the inner case

adapted to engage and lock the rack against sliding backwardly, a feed catch on the outer case adapted to engage and feed forwardly the rack in case the two cases are moved towards each other, and a spring lever attached to one of the cases and operated by pressure for raising the catches and interrupting the engagement between the said catches and the rack.

2. A pencil having a slidable lead comprising in combination an inner case provided with a longitudinally extending slot, an outer case encasing the inner case, the two cases being adapted to slide within one another, a longitudinally adjustable toothed rack in the inner case for feeding forwardly the slidable lead, the teeth of the said rack projecting into and being freely accessible by means of the longitudinal slot in the inner case, a locking catch on the inner case adapted to engage and lock the rack against sliding backwardly, a feed catch on the outer case adapted to engage and feed forwardly the rack in case the two cases are moved towards each other, and a spring lever provided with a semi-circular member attached to one of the cases and operated by pressure for raising the catches and interrupting the engagement between the said catches and the rack.

3. A pencil having a slidable lead comprising in combination an inner case provided with a longitudinally extending slot, a shorter outer case encasing the rear portion of the said inner case, the two cases being adapted to slide within one another, a longitudinally adjustable toothed rack in the inner case for feeding forwardly the slidable lead, the teeth of the said rack projecting into and being freely accessible by means of the longitudinal slot in the inner case, a locking catch on the inner case adapted to engage and lock the rack against sliding backwardly, a feed catch on the outer case adapted to engage and feed forwardly the rack in case the two cases are moved towards each other, and a spring lever attached to one of the cases and operated by pressure for raising the catches and interrupting the engagement between the said catches and the rack.

4. A pencil having a slidable lead comprising in combination an inner case provided with a longitudinally extending slot, an outer case encasing the inner case, the two cases being adapted to slide within one another, a longitudinally adjustable toothed rack in the inner case for feeding forwardly the slidable lead, the teeth of the said rack projecting into and being freely accessible by means of the longitudinal slot in the inner case, a locking catch on the inner case adapted to engage and lock the rack against sliding backwardly, a feed catch on the outer case adapted to engage

and feed forwardly the rack in case the two cases are moved towards each other, a bolt secured to the outer case and passing through a slit in the inner case, the said slit being of a length corresponding to the width of the bolt and of one tooth of the rack, whereby owing to the movement of the two cases against one another the forward-feed of the lead will be effected for the length of one tooth only, and a spring

lever attached to one of the cases and operated by pressure for raising the catches and interrupting the engagement between the said catches and the rack.

In testimony whereof I have signed my ¹⁵ name to this specification.

EMIL KROUTL.
